(57) **CLAIM**

We claim the ornamental design for a impression coping, as shown and described.

DESCRIPTION

FIG. 1 is a perspective view of an impression coping, showing the new design;

FIG. 2 is a front elevational view thereof, the rear elevational view, left-side elevational view, and right-side elevational view all being a mirror image thereof;

FIG. 3 is a top plan view thereof; and,

FIG. 4 is a bottom plan view thereof.

The broken lines in FIG. 4 depict environmental matter and form no part of the claimed design.
